CLARENCE J. SAMPLE, OF ST. LOUIS, MISSOURI

TRESTLE

Application filed March 28, 1930. Serial No. 439,825.

My invention relates to a separable trestle adapted to be used by plasterers, carpenters, masons and other workmen.

The object of my invention is to provide a trestle so constructed that it may be packed and transported in parts, and put together for use by skilled or unskilled persons.

Further objects of the invention are to improve the manufacture of trestles in the particulars of durability, ease of construction, convenience of handling when transporting same from one place to another, cheapness in cost of manufacture, ease of assembling and knocking down of structure, simplicity and security of bracing and locking members.

A still further object of the invention resides in novel means for securely holding the upper ends of the supporting legs of the trestle in socket members by wedge pressure, regardless of whether the legs are of single pieces carefully selected to properly fit into the sockets or selected from a single stray piece of wood, or from pieces laminated and even of different lengths.

A still further object of the invention resides in means for loosening the wedge grip against the upper end of the supporting legs.

With the above and other objects in view, the invention consists in the novel features of construction, arrangement and combination of parts hereinafter more fully described and finally pointed out in the claims hereto appended.

Referring to the accompanying drawings forming a part of this specification, wherein like characters of reference denote similar parts throughout the several views:

Fig. 1 is an outer end view of one of the trestle sections with the supporting legs applied thereto.

Fig. 2 is a side elevation of a trestle made in accordance with my invention.

Fig. 3 is a top plan view of the trestle.

Fig. 4 is a view partly in side elevation and partly in sectional elevation of one of the trestle sections.

Fig. 5 is a detail in side elevation with portions broken away showing the wedge

mechanism for locking the upper ends of the supporting legs in their respective sockets.

Fig. 6 is a sectional view of one of the supporting legs, showing a portion of one of the brace members and its locking member.

Fig. 7 is an end view partly in elevation and partly in cross section of the outer end of one of the trestle sections, showing the wedge mechanism and the bracing members.

Referring to the drawings, the reference character 1 designates supporting legs of the trestle, there being two pairs of legs joined, or connected together by two cross girds designated 2 disposed side by side and overlapping each other whereby the two pairs of legs are offset or set out of alignment. The two girds are supported by means of a pair of like S-shaped suitable hanger members 3, one of which is secured to each girth by means of a suitable fastening device 4 passing through each hanger member and entering its respective girth, to prevent the hanger members being lost when the two trestle sections are disconnected and separated.

The legs 1 are made of single pieces of wood of the desired dimensions, but if they are not accessible, two or more pieces of wood designated 1' and 1'' may be laminated to provide the legs for the trestle, as shown in Fig. 7.

Each girth member 2 is provided near one end and upon opposite side faces with a suitable preferably metallic socket member 5 having the wings 6 through which suitable fastening devices 7 pass and enter the girds for securing the sockets in position upon opposite sides of each girth member. Each pair of socket members for each girth are oppositely disposed and they are each provided with the top wall 8 which permits of an opening 9 adjoining the girth and each socket member has its outer wall preferably slanting outwardly from top to bottom. The side walls 10 of the socket are preferably parallel. The slanting outer walls of the socket members allow the legs to be spread apart at their lower ends to provide

a solid footing for the trestle and does not require that the upper side faces of the legs be slanting or beveled before they can enter the sockets 11 formed within the walls of the 5 socket member and the girth when applied thereto.

The bracing means for each half trestle section comprises a pair of preferably angle iron brace members 12 each having its inner 10 end bent at a suitable angle to the remainder of the member so as to lie substantially parallel with the sides of the girth member when applied thereto to permit the inner ends of the brace members to lay one upon 15 the top of the other under the girth member.

Each girth member is provided with a suitable depending eye shaped hanger member 13 the lower cross piece 14 of which is 20 adapted to be received in a notch 15 in the side walls of each angle iron brace member 12 for supporting the overlapped inner ends of the brace members.

The rear end of each brace member 12 has 25 a section of its top wall flattened out to lie in alignment with the outer side walls thereof which forms a shoulder 16 for each brace member adapted for engagement with the inner side face of each leg 1 to prevent rearward longitudinal displacement of the brace member after it is supported by the depending hanger 13.

A suitable flat tie and locking member 17 is employed with each pair of brace members 12 and is adapted to engage the outer side faces of each pair of legs 1. The tie member is provided with a right angularly disposed wall section extending from the upper edge of the tie member which is 35 adapted to be disposed between and engage the inner or opposed faces of each pair of legs at one end of the girth members, as will be apparent from Figs. 1 and 7. The tie members 17 are each provided upon their 40 lower edges near the ends thereof with a pair of notches 18 adapted to engage in the notches 19 in the upper edges of the flat end sections of the back pair of brace members for detachably locking the tie members with 45 the outer ends of the brace members to provide a rigid brace system for the trestle and to securely hold each pair of legs from any possible spreading movement after the brace members and tie members therefor have been 50 applied to each trestle section.

The above arrangement permits of easy and quick assembly of each trestle section and permits of it being readily knocked down or separated for transportation and storage.

It will be readily apparent that the bracing members can be readily removed by merely lifting the tie member from engagement with the ends of the bracing members 60

which allows them to be free for removal from the hanger member.

The means for securely holding the outer faces of each pair of legs in contact with the slanting walls of their respective socket members and to assist in preventing movement of the lower ends of the legs toward each other comprises a U-shaped wedge member 20 for each girth which spans the lower face of the girth with its legs 21 directed upwardly into the sockets adjacent the side faces of the girth. The legs 21 of the U-shaped member are preferably converging toward their free ends so that each leg of the U-shaped member will act as a wedge against the inner face of each leg to prevent lateral displacement thereof when held in its respective socket. The cross piece of the U-shaped wedge member is held in contact with the under face of a lever 22 which is hingedly connected at one end, as at 23, to one of the wings of the opposed socket members carried by the girths. The wedge member is held in position with relation to the lever by means of a bolt 20' carried by the girth and which passes through a slotted opening 24 in the lever and a slotted opening in the U-shaped wedge member, which bolt is provided with an adjusting nut 25 which can be loosened so that the lever can be lowered from one end to retract the wedge member from between the legs and the side faces of the girth when it is desired to remove the legs from the socket by loosening the frictional contact of the arms of the wedge member with the legs which they engage. Whenever the legs are 90 in position in their respective sockets the nut is tightened to draw the wedge members into their extreme uppermost wedge position so that there will be no play of the leg within the socket. The slotted opening in the cross piece 26 of the wedge members permits the wedge members to move laterally of the girth should one leg be a little narrower 95 than the other within its socket.

From the foregoing description, it is evident that the trestle above described can be easily and quickly assembled without the aid of tools by first inserting the legs into the sockets, then supporting the forward end of the braces over the hanger depending from each girth, then applying the tie member to the outer ends of the bracing members. When inserting the legs into the sockets, the wedge members will be moved upwardly thereby to provide means to prevent the legs from moving toward each other at their lower ends. After the legs have been inserted into the sockets, the nut on the bolt which passes through the wedge member is tightened to prevent the wedge members from accidentally dropping. When it is desired to disassemble the trestle, the nut is loosened, the lever is pulled down at one 100 105 110 115 120 125 130

end which loosens the wedge member and the legs are then free to be removed from the sockets after the tie member is detached from the ends of the brace member. After 5 the tie member has been removed, the brace members can then be lifted off of the hanger supporting the inner ends thereof.

The many advantages of the herein described invention will readily suggest themselves to those skilled in the art to which it appertains.

From the foregoing description, it is evident that a simple device for this purpose has been disclosed, but it is to be understood 15 that I do not desire to restrict, or limit myself to the very details of the construction shown and described, which is merely illustrative, it being obvious that changes, not involving the exercise of invention, may be 20 made without conflicting or departing from the spirit of the invention within the scope of the appended claims.

What I claim is:

1. In a trestle structure of a pair of like 25 trestle sections, each section comprising a girth, a pair of sockets carried by each girth, detachable legs extending upwardly into said sockets, a pair of detachable braces directed from each pair of legs to a point 30 under each girth, means for supporting the inner ends of said braces, means for detachably connecting the outer ends of said braces for locking them in position, wedge means adapted for engagement with each pair of 35 legs and means for loosening the wedge connection when the legs are to be removed from their respective sockets.

2. In a trestle structure, a pair of girths disposed side by side, S-shaped hangers for 40 connecting said girths, a pair of legs for each girth, means carried by each girth for receiving the upper end of each leg, a bracing member engaging each leg, means for detachably supporting the inner end of each 45 bracing member under the girth intermediate the ends of the girth and means engaging the legs and detachably connecting the outer ends of each brace member and drawing the outer ends of the brace members into contact 50 with the legs to prevent spreading movement of the legs.

3. In a trestle structure, a pair of girths disposed side by side, S-shaped hangers for connecting said girths, a pair of legs for 55 each girth, means carried on opposite sides of each girth to form opposed sockets to receive the upper ends of said legs, a bracing member engaging each leg, means for detachably supporting the inner end of each 60 bracing member under the girth intermediate the ends of the girth, means engaging the legs and detachably connecting the outer ends of each brace member and drawing the outer ends of the brace members into contact 65 with the legs to prevent spreading move-

ment of the legs, U-shaped wedge members carried by each girth the arms of which are adapted to enter the aforesaid sockets for engagement with the inner faces of the legs and means for releasing the arms of said wedge members from tight frictional contact with the inner faces of said legs. 70

4. In a trestle composed of two like trestle sections, each trestle section comprising a girth, a pair of opposed sockets carried by 75 the girth, legs having their upper ends receivable in said sockets, a pair of brace members, means for detachably supporting the inner ends of said brace members below the girth intermediate the ends of the girth, shoulders formed on said brace members near their outer ends adapted to engage the inner side faces of the legs, a tie member detachably connecting the outer ends of 80 said brace members, a U-shaped wedge member the arms of which extend upwardly into the opposed sockets and adapted to engage the inner faces of the legs and a pivotally supported lever for retracting the wedge member arms from tight frictional contact 85 with the inner faces of the legs. 90

5. In a separable trestle, a pair of girth members adapted to be positioned side by side, a hanger member carried by each girth for supporting the other girth in parallel relation and permitting of longitudinal adjustment thereof relative to each other, a pair of socket members carried by opposite faces of each girth near the outer ends thereof, a leg for each socket member, the upper end of which is receivable in its respective socket, a pair of brace members for each end of the assembled trestle, a hanger carried by each girth for supporting the inner ends of each pair of brace members, a detachable tie member connecting the outer ends of each brace member, a shoulder formed on each brace member for contact with the legs which the brace member engages, shoulders formed on the tie member for engagement with the inner faces of two opposed legs which the tie member is adapted to engage, a U-shaped wedge member carried by each girth the arms of which are adapted to extend upwardly into the opposed sockets at the outer ends of each girth, a lever hingedly supported at one end to each girth between the opposed socket members thereof, a bolt carried by each girth and passing through the lever and wedge members associated therewith and a nut carried by said bolt. 110

In testimony whereof, I have hereunto affixed my signature.

CLARENCE J. SAMPLE. 125
